UNITED STATES PATENT OFFICE.

ADOLPH W. RYBECK, OF MILWAUKEE, WISCONSIN, ASSIGNOR TO T. L. SMITH CO., OF MILWAUKEE, WISCONSIN, A CORPORATION OF WISCONSIN.

POWER DISCHARGE FOR MIXING MACHINES.

Application filed April 26, 1922. Serial No. 556,773.

To all whom it may concern:

Be it known that I, ADOLPH W. RYBECK, a subject of the King of Sweden, and resident of Milwaukee, in the county of Milwaukee and State of Wisconsin, have invented new and useful Improvements in Power Discharges for Mixing Machines, of which the following is a description, reference being had to the accompanying drawings, 10 which are a part of this specification.

This invention relates to certain new and useful improvements in material mixers and refers more particularly to a power actuated discharge spout for discharging materials from the mixing drum thereof.

In material mixers of that type more especially designed for mixing concrete for use in road or other construction work, it has been customary to swing the discharge 20 spout to and from discharging position by manually operated means and, by reason of the inner or receiving end of the spout intercepting the material in the drum when moved to discharging position, this operation is only effected by the expenditure of 25 considerable energy.

It is, therefore, a primary object of this invention to provide a discharge spout connectible with power operated means for 30 moving the same to and from discharging position.

This invention has for another of its objects to provide means for moving the discharge spout to and from discharging position which derives its power from the mixing drum drive.

It is a further object of this invention to provide power operated means for the discharge spout equipped with automatic stops 40 for disconnecting the spout from the power means when the same reaches either of its limits of movement.

This invention has for a still further object to provide a power operated discharge spout having an improved means for connecting the same with a drive unit whereby economy of manufacture and efficiency of operation are assured.

With the above and other objects in view 50 which will appear as the description proceeds, my invention resides in the novel construction, combination and arrangement of parts substantially as hereinafter described and more particularly defined by the appended claims, it being understood that such

changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a fragmentary view looking 65 at the forward or discharge end of a material mixing machine illustrating the manner of mounting the transmission drive for the discharge spout on the machine frame work;

Figure 2 is a fragmentary view, partly in side elevation and partly in section, looking on the plane of line 2—2 of Figure 1;

Figure 3 is a view, partly in transverse section and partly in elevation, taken 75 through the power transmission for the discharge spout on the plane of line 3—3 of Figure 4, and

Figure 4 is a view, partly in transverse section and partly in elevation, taken 80 through Figure 3 on the plane of line 4—4.

Referring now more particularly to the accompanying drawings, in which like numerals designate like parts throughout the several views; numeral 5 designates a forward transverse sill of a mixing machine from which extend two upwardly and inwardly inclined side brace beams 6, but one being illustrated in the drawings, and 7, a mixing drum which is rotatably mounted 85 on the platform of the machine in any suitable manner and adapted to be driven from a drive gear 8 connected with a suitable power unit, not shown, and meshing with a ring gear 9 secured about the periphery of 90 the drum.

The materials to be mixed are placed within drum 7 and, when they have been sufficiently mixed, are discharged through an opening 10 in the rear end of the drum by 100 projecting the inner end 11 of a discharge spout 12 into the drum through the opening 10 to intercept the materials. Spout 12 is mounted, in the manner hereinafter described, so that when its inner end 11 intercepts the materials within the drum, its outer discharge end 13 is positioned below its inner end and the materials readily discharged into any suitable receptacle.

Spout 12 is pivotally mounted between 110

two spaced arms or brackets 14 of a support 15, secured to beams 6 at their point of convergence, by a pivot 16 extending through the arms 14 and a pair of rearwardly extended arms or levers 17 centrally carried by a saddle 18 from which spout 12 is suspended.

Intermediately journaled in bearings 19 carried by beams 6 and bracket 15 is a rock shaft 20 on which is mounted, intermediate the arms of bracket 15, a lever 21, the outer end of which is connected to one end 22 of an adjustable rod 23. The other end 24 of rod 23 is pivotally mounted between the outer ends of levers 14 so that a clockwise rotation of shaft 20, with reference to Figure 2, will swing spout 12 in the direction of the arrow and position its end 11 within drum 7 to intercept the material therein and arrange its discharge end 13 on a lower plane to discharge materials intercepted by the spout.

Heretofore, manual means have generally been employed to move spout 12 to and from discharge position and, as considerable energy is required to project the inner end of the spout into the path of the material, I provide power means for operating shaft 20 whereby the operator can, by the manipulation of a foot pedal, connect shaft 20 with a source of power to swing the spout to either of its two positions, the power means being preferably automatically disconnected upon the spout reaching either of its limits of movement. In the present construction, I have found it highly desirable to obtain power for operating the spout from the drum drive gear 8 by meshing therewith a pinion gear 25 carried by the power take-off shaft 26 of a transmission unit 27.

Shaft 26 is journaled in bushings 28 within the casing of the transmission unit, and slidably splined on the shaft intermediate the bushings is a movable clutch member 29 having clutch faces 30 on opposite sides thereof adapted for engagement with clutch faces 31 of beveled gears 32 freely rotatably journaled on bushings 28. Journaled in the transmission casing transversely of a shaft 26 is a worm shaft 33 on one end of which is mounted a beveled gear 34 with which both of the gears 32 mesh, whereby connection of one gear 32 with shaft 26, by the engagement of the adjacent clutch face 30 with the clutch face of said gear, will rotate gear 34 in one direction and connection of the other gear 32 with shaft 26 will rotate gear 34 in a reverse direction, gear 34 being inactive when the clutch member is in an intermediate position.

Mounted on shaft 33 is a worm 35 with which meshes a worm wheel 36 fixed to a shaft 37, one end of which is positioned exteriorly of the transmission housing and has secured thereto a lever 38 with which the

lower end of an adjustable connecting rod 39 is pivotally connected, the upper end of rod 39 being pivotally secured to the outer end of a lever 40 fixed to shaft 20.

A rotation of shaft 37, through the medium of the transmission unit, in the direction of the arrow in Figure 1, will swing the spout into discharging position and, when the spout reaches its limit of movement, clutch 30 is moved to neutral position by an adjustable stop 41, carried by an arm 42 mounted on shaft 37, engaging the outer end of a lever 43. Lever 43 is carried by a gear shift rod 44 on which is mounted a forked arm 45 having bearing blocks 46 engageable in an annular groove formed in the clutch member.

When the spout is to be returned to inoperative position, rod 44 is rotated in a clockwise direction, with reference to Figure 4, by a pedal 45 to mesh the clutch member with the gear 32 to the left thereof to thus rotate shaft 37 in a direction reverse to the arrow in Figure 1 until an adjustable stop 46', carried by an arm 47 mounted on shaft 37, engages lever 43 and shifts the clutch member to neutral position.

Clutch member 30 is yieldably secured in neutral position by a spring 48 having a recessed or outstruck portion 49 in which a lug or projection carried by lever 43 is engageable when the same is in neutral position.

What I claim as my invention is:

1. In a material mixing machine, a discharge spout adapted to be moved into operative and inoperative positions, power operating means for the same, said means including a drive shaft and a driven shaft, shiftable means for disconnecting the latter from the former and causing its movement in reverse directions, a third shaft connected to said spout and adapted to cause the movement of the same, said third shaft being operated by said driven shaft, and elements carried by said third shaft and adapted to operate said shiftable means upon the completion of the movement of the spout to one of its said positions.

2. In a material mixing machine, a discharge spout adapted to be moved into operative and inoperative positions, power operating means for the same, said means including a drive shaft and a driven shaft, means shiftable upon said drive shaft for connecting the driven shaft thereto and operating the same in reverse directions, a third shaft connected to said spout and adapted to move the same into its several positions, said third shaft being operated by said driven shaft, and elements carried by said third shaft for operating said shiftable means upon the completion of the movement of the spout to one of its said positions.

3. In a material mixing machine, a dis-

- charge spout adapted to be moved into operative and inoperative positions, power operating means therefor, said means including a drive shaft and a driven shaft, means 5 slideable upon said drive shaft for connecting the driven shaft thereto and operating the same in reverse directions, a third shaft connected to said spout and adapted to move the same into its several positions, said third 10 shaft being operated by said driven shaft, and adjustable elements carried by said third shaft for operating said slideable means upon the completion of one movement of the spout.
- 15 4. In a material mixing machine, a discharge spout adapted to be moved into operative and inoperative positions, power operating means therefor, said means including a drive shaft and a driven shaft, means 20 slideable upon said drive shaft for connecting the driven shaft thereto and operating the same in reverse directions, means for operating said slideable means, a rock shaft for supporting said operating means, a plurality 25 of arms connected to said rock shaft for moving the same, a third shaft connected to said spout and adapted to cause the movement of the same, said third shaft being op- erated by said driven shaft, and elements 30 carried by said third shaft for engagement with one of said arms for operating said slideable means upon the completion of one movement of the spout.
5. In a material mixing machine, a discharge spout therefor and adapted to be 35 moved into operative and inoperative positions, power operating means for said spout, said means including a drive shaft and a driven shaft, means slideable upon said drive shaft for connecting the driven shaft there- 40 to and operating the same in reverse directions, means for operating said slideable means, a rock shaft for supporting said operating means, a hand lever connected to one end of said rock shaft and an arm at the 45 other end, a third shaft connected to said spout and adapted to cause the movement of the same into its several positions, said third shaft being operated by said driven shaft, and adjustable elements carried by 50 said third shaft for engagement with said arm upon the completion of either movement of the spout.

In testimony whereof I affix my signature.

ADOLPH W. RYBECK.
